UNITED STATES PATENT OFFICE.

LOUIS BELL, OF NEWTON, MASSACHUSETTS, ASSIGNOR OF ONE-HALF TO HIMSELF AND
ONE-HALF TO WALTER G. WOLFE, OF GREENWOOD, MASSACHUSETTS.

HEADLIGHT-LENS

1,277,364.

Specification of Letters Patent.

Patented Sept. 3, 1918.

Application filed December 1, 1916. Serial No. 134,428.

To all whom it may concern:

Be it known that I, LOUIS BELL, a citizen of the United States, residing at Newton, county of Middlesex, Commonwealth of Massachusetts, have invented certain new and useful Improvements in Headlight-Lenses, of which the following is a specification.

This invention relates to improvement in headlight lenses, and particularly to improved means for avoiding glare from the headlight of vehicles. Various difficulties have developed in the production of devices of this sort, and it is to the overcoming of these difficulties that my present invention relates.

The light shed from the ordinary parabolic reflector is instead of a parallel beam, a sheaf of divergent rays owing to frequent marginal errors of the parabola and dimensions of the filament or flame.

My present invention contemplates a combined utilization of the somewhat varying rays from the forward part of the reflector. Briefly, I provide for the diffusion of the erring marginal rays, the defraction and longitudinal control of the central portion of the beam. As illustrative of my invention I have shown embodiments productive 30 of the effects above indicated as desirable and which well illustrate the principles of my invention.

Throughout the specification and in the accompanying drawings, like reference characters are employed to indicate corresponding parts, and in the drawings:

Figure 1 is a view of a lens in accordance with my invention.

Fig. 2 is a vertical sectional view of the same on the axis A B.

Fig. 3 is a section on the axis of the horizontal cylindrical curvature, and

Fig. 4 is a central vertical section through a lamp equipped with a lens in accordance with my invention.

My lens consists of the usual circular disk or screen employed to form the front of the headlight and adapted to be disposed in front of a parabolic reflector, not shown, but is formed with an annular rim or edge 1 preferably having parallel faces and of materially greater width than the frame of the front of the lamp in which it is set. This rim 1 while it preferably has substantially

parallel faces is roughened upon one or both such faces either by stippling, ribbing or corrugating, radially, or in any other manner so as to form a diffusing surface which will be exposed within the frame of the lamp and through which the marginal rays of erratic divergence will pass as strongly difused light.

I have found that the common practice of making the circumferential edge of a headlight lens in the form of a plane annulus of clear glass either with or without a circumferential bead is practically objectionable in that it gives no security of locking the lens against accidental rotation due to vibration of the car, and in fitting the lens to lamp fronts of slightly varying diameters the risk of an annulus of clear glass being exposed, from which there may be serious glare.

In the case of prismatic lens fronts it is equally objectionable to carry the prisms to the extreme periphery of the front since it becomes difficult to secure a dust-tight joint and the strain of the clamping device whatever it may be being borne at the apexes of the prisms. There is risk of strain and cracking of the lens. There is also, in case it is necessary to trim down the diameter of the lens slightly to fit a front, considerable risk of chipping and damaging the prism structure. I therefore provide in the structure of this invention a diffusing annulus surrounding the prismatic redistributing portion of the lens to an extent maintaining practical uniform thickness to the extreme periphery of the lens disk. This is stippled or otherwise roughened so that it both disperses the light and furnishes a surface so roughened as to hold the lens against turning from vibration.

Within this annular portion 1 I provide on the interior face of my lens top and bottom prismatic elements preferably developed as a cylindrical convexity of horizontal axis C D and shaped to secure the control and predetermined vertical dispersion of the rays of the light transmitted within the diffusing annulus 1. On the exterior surface of the lens, I form a laterally diverging element preferably being a cylindrical concavity in this instance of vertical axis A B. This is so shaped as to secure the control and predetermined lateral dispersion of the

rays within the diffusing annulus. These axes A B and C D of the inner and outer cylindrical curved surface cross each other at right angles but not necessarily at the center of the lens as hereafter set forth.

It may further be pointed out at this time that the planes in which these axes lie may be in substantial parallelism or at an angle to each other. Furthermore of these two faces, either may be ahead or instead of being on opposite sides of the lens they may be merged into a single face of compound curvature. One or both surfaces may be developed in the Fresnel form. Referring to Fig. 1 it will be noted that the cylindrical curvature of horizontal axis is indicated as preferably intersecting the vertical axis of the cylindrical curvature of the outer face below center. This effects a better distribution of the divergent rays in the upper portion of the light beam so as to bring them down below the horizontal while still redistributing to somewhat lesser extent any divergent rays produced in the lower part of the reflector and which are intercepted by the roadway more adjacent to the car, thus lifting them toward the horizontal. In the same manner the vertical axis of the exterior cylindrical curvature may be decentered so as to produce better convergence and overlapping of roadway intercept of rays from a pair of lamps. The annular dispersing area 1 in the margin of the lens 2 is preferably carried from the extreme periphery of the lens to a sufficient distance so that it will be exposed well within the marginal overlapping of the frame of any lamp front.

The stippling or other roughening of this diffusing annulus so as to afford a considerable margin is not only of advantage on account of its function in taking care of the marginal errors of different parabolas, but it being uniform clear to the periphery makes of this area an element which may be trimmed down to fit a lamp of peculiar diameter without inconvenience. The two faces of this annulus are therefore preferably parallel faces although there may be slight divergence. The stippling or other roughening of this annulus to the periphery is furthermore of mechanical advantage as a means of preventing the accidental turning of the lens and the loss of adjustment of its axes under the vibration of the road or by careless handling.

Various modifications in the form and construction of my invention may obviously

be resorted to if within the limits of the appended claims.

What I therefore claim and desire to secure by Letters Patent is:

1. In combination, a headlight having a lens clamping front, a lens having refracting elements disposed to deflect the beam downward in the vertical plane and laterally in the horizontal plane and a roughened margin entirely about the edge thereof and extending to within the grasp of said clamping front.

2. A headlight lens having a central light transmitting area formed with cylindrical surfaces of crossed axes of opposite sign for regulating the distribution of light passing through such area, and a marginal roughened area.

3. A headlight lens formed with cylindrical surfaces developed from crossed axes of opposite sign and a marginal diffusing area reaching the periphery of the lens.

4. In combination with a headlight having a reflector for substantially parallel rays, a lens having a central light transmitting area formed with refractive surfaces cylindrically developed from crossed axes and of radii of opposite sign.

5. In combination with a headlight having a reflector for substantially parallel rays, a lens having a central light transmitting area formed with refractive surfaces cylindrically developed from crossed decentered axes and of radii of opposite sign.

6. In combination with a headlight having a reflector for substantially parallel rays, a lens formed with refractive surfaces cylindrically developed from vertically and horizontally crossed axes and of radii of opposite sign.

7. In combination with a headlight having a reflector for substantially parallel rays, a lens formed on its opposite faces with surfaces of cylindrical curvature of opposite sign, the axes of cylindricity being crossed at substantially right angles.

8. A headlight lens having light distributing surface formed with concave and convex cylindricity developed on substantially vertical and horizontal axes respectively.

In testimony whereof I affix my signature in presence of two witnesses.

LOUIS BELL.
